UNITED STATES PATENT OFFICE.

VANDIVER J. VAN HORN, OF CHICAGO, ILLINOIS, ASSIGNOR TO UNION SPECIAL MACHINE COMPANY, OF CHICAGO, ILLINOIS, A CORPORATION OF ILLINOIS.

ORNAMENTAL-STITCH SEWING-MACHINE.

1,134,564.

Specification of Letters Patent.

Patented Apr. 6, 1915.

Application filed May 11, 1907. Serial No. 373,069.

To all whom it may concern:

Be it known that I, VANDIVER J. VAN HORN, a citizen of the United States, residing at Chicago, in the county of Cook, State of Illinois, have invented certain new and useful Improvements in Ornamental-Stitch Sewing-Machines, of which the following is a description, reference being had to the accompanying drawing and to the letters and figures of reference marked thereon.

My invention relates to new and useful improvements in sewing machines, and has for its object to produce an ornamental stitching machine which may be operated to form an ornamental stitch upon a fabric, or between the edges of spaced fabrics, wherein it would also serve the purpose of securing the fabrics together, or said stitch may be formed at the edge of the fabric, thus producing a finished edge for said fabric.

My invention consists in the combinations and arrangements of parts hereinafter shown, described and set forth in the claims.

In the accompanying drawings which show one form of my invention, Figure 1 is a front plan view of a sewing machine embodying my invention; Fig. 2 is a rear plan view of the same; Fig. 3 is an end elevation of the same; Fig. 4 is a top plan sectional view, showing the thread-carrying member and the loop-forming devices; Fig. 5 is a detail view, showing the relation of the needles to the thread-carrying member and the loop-forming devices with a loop formed for the entrance of the right hand needle; Fig. 6 is a view similar to Fig. 5, showing the thread-carrying member in its advanced position; Fig. 7 is a view similar to Fig. 5, showing the loop formed for the entrance of the left hand needle; Fig. 8 is a bottom perspective view of the loop-forming hooks, showing also the manner of spreading the loop for the entrance of the needle; and Fig. 9 is a detail view, showing the presser foot and the fabric-guiding fingers carried thereby.

The work support 1, the overhanging arm 2, the needle lever 3, the needle bar 4, the link 5 connecting the needle bar with the needle lever, and the link 6 for connecting the needle lever to the main shaft 7, are of the usual construction, and will not need further description. The needle bar 4 carries at its lower end a needle head 8, carrying needles 9, 10. Said needles are mounted

upon said needle head 8, so that the same may be adjusted relative to each other, and to the axis of the needle bar. Said needles 9 and 10 are preferably set diagonally to the line of feed, as clearly shown in Figs. 4 to 7 of the drawings.

Coöoperating with said needles is any suitable complemental stitch-forming mechanism, preferably of such a character that two independent lines of stitching will be performed, although it is obvious that any other form of mechanism may be substituted therefor, if desired. This complemental stitch-forming mechanism being of the usual form is not illustrated in the drawings.

Mounted on the overhanging arm 2 of the machine are suitable tension devices 12, 13. The needle lever is provided with suitable thread eyelets 14, 15. Intermediate the eyelets 14 and 15 is a thread eyelet 16, mounted on an arm 17 pivoted to the head of the machine. The arm 17 is provided with a segment gear, which coöperates with a rack 18 carried by the presser bar. The needle threads after passing through the tensions 12, 13, are led to the eyelets 14, 16, 15, and then to suitable eyelets 19 at the upper end of the needle bar. The needle threads are led through the controlling wire 20, mounted on a post 21, supported by the head of the machine. The needle thread after leaving the thread eyes 19, pass between the pins 22, 22, and through the tension 23 carried by the needle bar collar, and thence in the rear of guiding fingers 24, carried by the needle head to the needle eyes. The tension 23 is formed of the usual disks which are held in contact by a coiled spring 24^a, surrounding the post on which the disks are mounted. This tension device is carried by the collar to which the link 5 is connected.

The operation of the stitch-forming mechanism above described, will be obvious. As the needle lever descends, carrying with it the thread eyelets 14 and 15, thread will be drawn from the supply, and as the needle lever rises, slack is given up to the needle. The thread eyelets 19 moving from a position below the thread-controlling wire 20 to a position above the same, operate to take up the thread and set the stitch. The amount of thread drawn from the supply on the formation of the stitch, will vary according to the thickness of the fabric, through the varying positions of the controlling arm 17,

which is connected to the presser foot and is raised or lowered through said presser foot as the fabric varies in thickness.

The presser bar 25 is mounted in the over-hanging arm, and is held in engagement with the fabric by a spring 26. Said presser bar 25 may be raised by the hand lever 27, or by the lever 28 pivoted to the head of the machine, and which is connected to a suitable knee lever or foot treadle. This presser bar and its operating mechanism is of the usual construction. The presser bar carries at its lower end a presser foot 29 comprising a main section and a movable section, which is pivoted thereto by a suitable pivot pin 30. This presser foot as clearly shown in Figs. 5 to 7, is provided with needle slots 31 and 32, which needle slots are connected by a cross slot, thus forming a tongue 33, over which threads may be laid in the stitching operation, and as the feed of the fabric takes place, said thread will slip off from the end of said tongue. At its forward end said presser foot is slotted, forming projecting fingers 34 and 35. Mounted on the finger 35 is a fabric guide 36. Said guide is provided with a shank 37, which extends up over the finger 34, and is slotted, whereby said guide may be adjustably attached to said finger by a suitable screw passing through the slot into the finger. The finger 34 is provided with a similar fabric guide 38, which is also adjustably attached thereto. The object of these guides 36 and 38 is to guide the edges of two spaced fabrics so that the same may be presented to the needles.

The thread-carrying finger 39, having a thread eye 40 in its outer end, is pivoted to a bracket 41 extending outwardly and forwardly from the head of the machine, as clearly shown in Fig. 4 of the drawings. The outer face of the bracket 41 is formed on the arc of a circle, the center of which is the axis of the needle bar. Said bracket 41 carries an extension 42, similarly curved, and adjustably held on said bracket 41 by means of a screw 43. The thread-carrying arm 39 is mounted on a pivot 48, carried at the outer end of the extension 42.

The thread arm 39 is so proportioned that the path of movement of the thread eye 40 intersects the axis of the needle bar, and consequently said thread eye in its oscillations will pass midway between the spaced needles 9 and 10. Owing to the shape of the bracket 41, the extension 42 may be adjusted so as to change the position of the fulcrum point 43 of the thread-carrying arm 39, and the thread eye in all its adjusted positions will still intersect the axis of the needle bar, passing midway between the needles. The thread arm 39 is connected to a link 44 by means of a suitable ball joint 45. The opposite end of the link 44 is connected by a similar ball joint to a depending arm 46, carried

by a sleeve 47, loosely mounted upon the shaft 48. Said sleeve 47 is oscillated by means of a link 48 connected to a suitable eccentric 49, carried by the main shaft 7.

Coöperating with the thread-carrying finger 39 is a loop-forming device 50, which is provided with thread-engaging hooks 51 and 52. Said loop-forming device 50 is pivoted as at 53, to the rear end of the extension member 42. Said loop-forming device 50 is provided with an arm 54, which is connected by a link 55 to a depending arm 56, rigidly secured to the shaft 48 at the rear of the machine. Said shaft 48 has secured thereto a collar 57, to which is pivoted a suitable eccentric strap 58 coöperating with an eccentric 59, carried by the gear wheel 60, mounted upon a bearing carried by the over-hanging arm. Said gear wheel 60 receives its rotation from a gear wheel 61 mounted on the main shaft. It will be noted that the relative size of the gear wheels 60 and 61 is such that the loop-forming device will receive one oscillation to every two oscillations of the thread-carrying finger, and the reciprocation of the needle bar.

The thread for the thread-carrying finger is led through a suitable tension 62, and then through eyelets 63, 64, carried by an adjustable bracket on the head of the machine. From the eyelet 64 said thread is led through a suitable eyelet 65, and then through a thread eye 66 on the thread-carrying member 39. A thread eye 67 mounted on the needle lever 3 vibrates between the thread eye 63 and 64, and operates to pull the thread from the supply.

The operation of the thread-carrying finger and loop-forming device is as follows: Starting with the needles in the raised position and the thread finger is at this time in its rear position, while the thread hook 52 is in engagement with the thread carried by the thread finger 39, and has formed a loop in said thread, holding said loop spread for the entrance of the needle 9 in its descent, and as said needles move downward, the thread finger 39 will move forward to the position shown in Fig. 6. The thread hook 52 holds the loop formed in the thread of the thread-carrying finger until the needle has entered the same, and then said thread hook moves to the left, as shown in Fig. 6 and the thread hook 51 is brought into engagement with the thread carried by the thread finger.

Inasmuch as the loop-forming device 50 oscillates only once to every two vibrations of the thread finger and the needles, said needles will move to their lowest position to form the stitch, and rise again to their extreme upward position by the time the thread hook 51 has reached the position shown in Fig. 7. As the needles descend for the formation of the next stitch, the needle

10 will enter the loop formed in the thread carried by the thread finger, and which is at this time held spread for the entrance of the needle by said hook 51.

5 It will be noted from Fig. 8 that the thread hooks 51 and 52 are provided with a thread groove leading from the base of the hook longitudinally of the shank of the thread-carrying device. The purpose of 10 this thread groove is to receive the thread of the thread-carrying member, and as it is drawn into said groove the loop is slightly spread by said movement of the thread.

As clearly shown in Fig. 5, the thread of 15 the thread-carrying finger is formed into loops, which are laid alternately for the entrance of the needles and the finished stitch has the appearance of a figure 8, the loops of 20 which are secured by the parallel lines of stitching.

If a single piece of fabric be led to the machine, the ornamental thread will be laid back and forth from one needle to the other, and secured to said fabric by the parallel 25 lines of stitching. If, however, two spaced fabrics be guided by the edge guides to the machine, the edges of said fabrics will receive the lines of stitching, and the ornamental thread will extend from the edge of 30 one fabric to the edge of the other fabric, thus securing the two fabrics together. If a single piece of fabric be inserted in one of the edge guides, said fabric will have a line of stitching passed therethrough, adjacent 35 its edge, and the ornamental thread will extend outward from the edge of the fabric, having its outer loops secured by a line of stitching formed by the other needle, thus forming a finished edging for a fabric.

40 After the needles are properly adjusted, the thread-carrying finger and the loop-forming device may be also adjusted by the movements of the extension 42 on its supporting bracket, so that said finger and 45 looping device may be properly positioned for cooperation and for properly presenting the loops of thread for the needles.

It will be noted that the thread-carrying 50 finger is formed on the arc of a circle, the center of which is the pivotal support of said finger. By thus forming the finger all points thereof will swing across the axis of the needle bar and pass between the needles without striking the same.

55 It will be obvious that a fabric or fabrics may be operated upon by the machine herein described in various ways, forming ornamental stitches of various characters.

Having thus described my invention, what 60 I claim as new and desire to secure by Letters Patent, is:—

1. A sewing machine, including in combination a plurality of needles, a presser foot, having connected needle slots, forming 65 a tongue extending between the needles, a

thread carrying member, and loop forming devices coöperating with said thread carrying member for forming loops for the entrance of said needles, and spaced fabric guides for guiding strips of fabric with 70 their edges separated, whereby the edges of fabric are engaged by the respective needles, and said edges joined by the connected loops.

2. A sewing machine including in combination, a plurality of needles, a presser foot 75 having connected needle slots forming a tongue extending between said needles, fabric guides carried by said presser foot, a thread-carrying member and loop-forming devices coöperating with said thread-carrying member for forming loops for the entrance of said needles; substantially as described.

3. A sewing machine including in combination, a plurality of needles, a thread-carrying member, a bracket for supporting said thread-carrying member, means for adjusting said bracket and looping devices carried by said bracket and coöperating with said thread-carrying member for forming loops 90 for the entrance of said needle; substantially as described.

4. A sewing machine including in combination, a plurality of needles, a thread-carrying member, a bracket for supporting said thread-carrying member, said bracket being curved in an arc the center of which is centrally between said needles, means for adjusting said bracket and looping devices coöperating with said thread finger for 95 forming loops for the entrance of said needles; substantially as described.

5. A sewing machine including in combination, a plurality of needles, a thread-carrying member, an adjustable bracket on 100 which a said thread-carrying member is pivoted, a loop-forming device pivoted upon said bracket, and means for positively operating said thread-carrying member and said loop-forming device; substantially as described.

6. A sewing machine including in combination, a plurality of needles, a presser foot, fabric guides carried by said presser foot, a thread-carrying member and loop-forming hooks coöperating with the thread-carrying member to form loops for the entrance of said needles; substantially as described.

7. A sewing machine including in combination, a plurality of needles, a presser foot, 120 adjustable fabric guides carried by said presser foot, a thread-carrying finger and looping devices coöperating with said thread-carrying finger to form loops for the entrance of said needles; substantially as 125 described.

8. In a sewing machine having a plurality of needles, a thread carrying member, a double jawed hook coöperating with said thread carrying member, and means to os- 130

5 cillate it, to carry a thread in front of said needles, said double jawed hook being provided with means to spread the loop of thread carried by it; substantially as described.

9. In a sewing machine, a needle bar, a needle, a second thread-carrying implement, and a coöperating device for carrying a loop of thread under the path of the needle, the 10 axes of the thread-carrying implement and the axis of the coöperating device being arranged in an arc of a circle struck from the axis of the needle bar and means whereby the axes of said devices may be adjusted relative to the needle; substantially as described.

10. In a sewing machine, a plurality of needles, a thread-carrying implement reciprocating in a path between said needles, a 20 double jawed implement coöperating therewith to carry loops of thread alternately in front of said needles, a device for taking up the thread carried by the thread-carrying implement, as the double jawed implement casts off the thread, and to give slack as the double jawed implement enters the loop; substantially as described.

11. A sewing machine including in combination a plurality of needles, a thread carrying member, an adjustable bracket on 25 which said thread carrying member is piv-

oted, a loop forming device pivoted upon said bracket, means for operating said thread carrying member, means for operating said loop forming device, and means whereby said bracket may be adjusted, said bracket being curved so as to lie substantially in the arc of a circle, the center of which is the axis of the needle bar.

12. A sewing machine including in combination 40 a work support, an overhanging arm, a plurality of needles, a thread carrying member, thread looping devices coöperating with said thread carrying member for forming loops for the entrance of the needles, a 45 main shaft, means for reciprocating the needles from said main shaft, an eccentric, a two to one gearing for rotating said eccentric from said main shaft, a rock shaft mounted in said overhanging arm, means 50 for oscillating said rock shaft from said eccentric, and means connected to said rock shaft for oscillating said looping devices whereby loops are formed in the thread carried by said thread carrying member and 55 presented alternately to said needles.

In testimony whereof I affix my signature, in presence of two witnesses.
